UNITED STATES PATENT OFFICE.

EMIL R. FRANK, OF SIOUX CITY, IOWA, ASSIGNOR OF ONE-HALF TO HUGH R. DEALY, OF SIOUX CITY, IOWA.

OIL AND GASOLENE MEASURE.

1,301,677.

Specification of Letters Patent. Patented Apr. 22, 1919.

Application filed December 15, 1917. Serial No. 207,321.

To all whom it may concern:

Be it known that I, EMIL R. FRANK, a citizen of the United States, residing at Sioux City, in the county of Woodbury and State of Iowa, have invented certain new and useful Improvements in Oil and Gasoline Measures; and I do hereby declare the following to be a full, clear, and exact description of the invention, such as will enable others skilled in the art to which it appertains to make and use the same.

This invention relates to improvements in liquid measuring devices and has for one of its objects the provision of a device of this character employing a plurality of containers varying in sizes which are adapted to be filled and the contents of either may be dispensed independently of the other so that a certain amount of liquid may be obtained by draining a certain container.

Another object of this invention is the provision of means whereby the containers may be filled from a single source.

A further object of this invention is the provision of means for admitting air to the containers so that the liquid therein may be drained or dispensed therefrom.

A still further object of this invention is the provision of an oil and gasoline measure of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:

Figure 1 is a front elevation of an oil or gasoline measure constructed in accordance with my invention, and

Fig. 2 is a detail sectional view of the valve for admitting air to the containers.

Referring in detail to the drawing, the numeral 1 indicates a supporting structure consisting of vertical supporting legs 2 which have formed upon their lower ends feet 3 that may be secured in any well known man-

ner to a foundation for supporting the frame 1 in a vertical position. The legs 2 are connected by upper and lower longitudinal members 4 and 5 which are constructed of pipes as well as the legs 2. The pipes forming the members 4 and 5 and the legs 2 are connected together by couplings as clearly illustrated in Fig. 1.

The member 4 is provided with a plurality of spaced openings to receive feed pipes 6 which have formed thereon collars 7 that rest upon the member 4 for limiting the movement of the feed pipes within the openings of said member. The feed pipes 6 are connected to T-couplings 8 that are connected by pipe sections 9 forming a supply pipe 70 which may be connected in any well known manner to a supply source. The feed pipes 6 after extending through the openings in the member 4 have connected thereto valves 10 to which are connected pipes 11. The pipes 11 are connected to transparent containers 12 that vary in sizes as clearly illustrated in Fig. 1 and which are adapted to receive a supply of liquid from the supply pipes heretofore mentioned by opening the valves 10. The containers 12 may vary in sizes from a container capable of holding fifteen gallons down to a quart or the like.

The valves 13 are connected to the lower ends of the containers by means of pipes 14 and have connected thereto outlet pipes 15 which extend through openings in the member 5 and are connected to T-couplings 16. The T-couplings 16 are connected by a plurality of pipe sections 17, the outer one of the series extending through the legs 2 forming a support for the lower ends of the containers. One of the outer pipe sections has threaded thereto a closure cap 18 while the other outer section is screw threaded as illustrated at 19 for the purpose of having a hose or the like connected thereto so that the liquid passing from the containers may be dispensed into an automobile or other device. Each of the containers 12 have formed thereon internally threaded bosses 20 to which are threaded plugs 21 having conical openings 22. Rods 23 extend through the conical openings 22 and have secured to their lower ends conical shaped floats 24 which are adapted to close the conical openings 22 as the containers become filled with liquid. Arcuate shaped members 25 are se-

cured to the upper ends of the rods 23 for the purpose of limiting the downward movement of the floats within the containers.

In operation, the containers are filled by 5 opening the valves 10 and after they have been filled, the valves 10 are closed cutting off the supply of liquid. When a certain amount of liquid is desired, such as ten 10 gallons or the like, the corresponding container 15 is manipulated by operating its respective valve 13 permitting the contents thereof to flow therefrom into the outlet pipe 17 whence it may be gathered in a suitable receptacle from the screw threaded end 19 or be dispensed into the tank of an automobile or the like.

From the foregoing description taken in connection with the accompanying drawing, it will be noted that a device has been provided 20 whereby a person may readily determine that he is receiving the correct amount of liquid by noticing the condition of the container before starting the dispensing operation and upon the entire amount of the 25 liquid being dispensed from the respective container, the purchaser is assured that he has received the exact amount of liquid, as the containers are transparent so that the amounts of liquid within the containers can 30 at all times be determined.

While I have shown and described the

preferred embodiment of my invention, it will be understood, that minor changes in construction, combination and arrangement of parts may be made, without departing 35 from the spirit and scope of the invention as claimed.

Having thus described my invention, what I claim is:

A measuring device comprising vertically 40 disposed and relatively spaced supporting legs, upper and lower relatively spaced longitudinally extending members connecting said legs and having spaced alining openings, inlet and outlet pipes extending 45 through the openings of the upper and lower members respectively, transparent measuring receptacles of different sizes connecting the inlet and outlet pipes, valves controlling the flow of fluid through said pipes, collars 50 formed on the inlet pipes and resting on the upper longitudinal member for supporting the receptacles, means supplying fluid to the inlet pipes and a main outlet pipe connected to the outlet pipes. 55

In testimony whereof I affix my signature in presence of two witnesses.

EMIL R. FRANK.
